UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A SPOON, &c.

SPECIFICATION forming part of Design No. 20,838, dated June 16, 1891.

Application filed May 8, 1891. Serial No. 392,110. Term of patent 7 years.

To all whom it may concern:

Be it known that I, AUSTIN F. JACKSON, residing at Taunton, in the county of Bristol and State of Massachusetts, have invented and produced a new and original Design for the Handles of Spoons, &c., of which the following is a specification, reference being had to the accompanying drawing, in which the figure represents a face view of the spoon.

For this design I have adapted and devised figures and symbols mindful and commemorative of the historic character Columbus, the discoverer of America.

My design is the handle ornamentation, which consists in the figure of a man representing Columbus in erect position, attired in the costume of the period in which he lived, his right arm being uplifted, his hand grasping his sword near the handle, holding it in an inverted position, his left arm hanging down, his left hand holding the staff of a flag, the folds of which fall downward to the rear of his body. Surrounding this figure is an oval-like ornamental border, the lower end of which is formed into a central ornament, under which a transverse wreath-

like band ornament is represented. The upper end of the spoon is curved outward, then inward, and then upward, such curved portions forming the upper end of the ornamental border, which terminates in a foliage cluster on the inner edges of the said curved portions.

a indicates the figure; *b*, the ornamental border; *c*, the foliage cluster; *d*, the transverse wreath-like ornament. Upon the shank of the handle, below the ornament *d*, are represented the words and numerals "Columbus, 1492," which, however, form no part of my design and may be omitted.

What I claim is—

The design for the handles of spoons, forks, knives, &c., which consists in the handle ornamentation, consisting of the figure *a*, the border *b*, the upper end of which terminates in a foliage cluster *c*, and the transverse ornament *d*, all substantially as herein shown and described.

AUSTIN F. JACKSON.
